UNITED STATES PATENT OFFICE

2,646,328.

COVER CONSTRUCTION FOR WORKTABLES

Carl S. Dayton, Bridgeport, Conn., assignor to
General Electric Company, a corporation of
New York

Application December 21, 1949, Serial No. 134,237

2 Claims. (Cl. 312—289)

1

This invention relates to an improved cover construction for work tables. It has for a particular object the provision of a cover construction which, when open, provides a convenient shelf structure at the rear of the table. My invention is well adapted for use with tables supporting domestic ironing machines, and in such association has as an object the provision of a simple, relatively inexpensive, ironing machine cabinet which when opened provides substantial shelf area on which may be laid the articles which have been pressed, or accessories such as sewing kits and the like. Yet another object is the provision of an ironing machine cabinet having a simplified cover construction which permits the cabinet to be arranged in series with permanently installed cabinets or accessories pursuant to the presently popular concepts of laundry and kitchen architecture.

In presently preferred forms of my invention I use a relatively conventional table or base structure, and affix to said base a cover having a fixed and a movable element so associated that in one position they provide a suitable closure and in another position provide a shelf-like arrangement having a rear guard wall. Optionally the cover construction may include side wings which fold down to provide additional shelf space.

Other features and advantages of my invention will be apparent from the following specification, read in conjunction with the accompanying drawing, in which Fig. 1 is a perspective view of one embodiment of my invention with the cover closed; Fig. 2 is a perspective view of the apparatus of Fig. 1 with the cover opened and the ironing machine ready for use; Figs. 3 and 4 are fragmentary side elevations, in section showing the relationship of the cover components with the cover respectively in closed and open position; Fig. 5 is a plan section taken through the end portions, only, of the cover element when in the Fig. 4 relationship; Fig. 6 is a perspective view of a second form of my invention, the cover being open; Fig. 7 is a partial end elevation in section showing the cover of Fig. 6 closed; and Fig. 8 is a perspective view of a third form of the invention with the cover open and the side closures in shelf forming position.

I have chosen to illustrate my invention in association with a domestic ironing machine. Referring initially to Figures 2 and 3, an ironing machine 1 of the domestic flatplate type is mounted on a table surface 2 of a suitable base structure having appropriately braced leg forming panels 3. The ironing machine has been repre-

2

sented as similar to that shown in United States Patent No. 2,135,266, granted November 1, 1948, to George W. Wardwell, Jr. In such machine a cylinder 4 is supported on the table top by a flange 5 engaging the same; the cylinder contains a combined piston and fluid pressure generation means for actuating a padded buck 6 on which the articles to be pressed are laid. Swingably carried relative to the buck, as by a carriage 7 10 pivotally mounted on the cylinder 4, is a pressing shoe 8. Pursuant to the teachings of said Wardwell patent the shoe 8 has a heated, smooth, ironing surface against which the buck presses the articles previously laid thereon. The operator draws the shoe manually from its home position of Fig. 3 to the operating position of Fig. 4, in which the shoe is over the buck in registry therewith. Thereupon a circuit is closed to energize the pressure generating means to propel 15 the buck upwardly against the shoe. The linkage and spring organization schematically shown at 9 is merely to counterbalance the shoe for easy operation.

The cover in the Fig. 1 embodiment comprises an upper member having a top portion 10 and a front wall portion 11, and an under member having a rear wall portion 12 and a forwardly extending top portion 14. The under member is rigidly secured to the table top forwardly of the rear edge thereof as by welding or otherwise securing to the table top a channel member 15, desirably integral with said cover member. The channel is suitably shaped intermediate its end to accommodate the carriage 7 as appears in Fig. 4. The side flanges 16 strengthen the walls 12, 14, so that the under cover member provides secure support for the upper member when the latter is in closed position. Thus the top wall 10, suitably surfaced, may be used as a kitchen or laundry work table.

10 The respective cover elements are pivotally and
slidably associated with each other so that the
upper member may be raised from its Fig. 3 po-
sition and dropped into its Fig. 4 position for ac-
cess to the table 2. To that end I suggest the em-
45 ployment of channel-like rails 17 securely fixed
to the rear wall 12 and rollers 18 carried on
brackets 20 affixed to wall 10. The upper ends
21 of the rails 17 may operate as stops to prevent
50 separation of the rolls therefrom. It will be
noted that the rails 17 are so placed relative to
the rear edge of the table 2 that the cover mem-
ber 10 will be in vertical alignment with the rear
wall 22 of the table structure. I utilize such di-
55 mensional relationship to employ one or more

rigid brackets 23 secured to and extending upwardly from the rear wall 22 to cooperate with the rear wall structure of the under cover member to support the upper member when in its raised position. Said brackets are preferably of angle or channel formation of limited projection beyond wall 22 so as to permit the ironer cabinet to be placed close against the building wall.

The operating relationship of the upper and lower cover members clearly appears in Figs. 3 and 4. When in the Fig. 3 position, also represented by Fig. 1, the rear wall 12 forms the rear wall of the cover and the top wall 10 and forward wall 11 of the upper member form the top and forward closure portions of the cover. The buck and shoe of the ironer are completely enclosed. When the cover is raised to its Fig. 4 position, the upper wall 14 provides a shelf of substantial area and the wall 10 forms a rear wall which serves as a guard wall for articles placed on the shelf.

As shown in Fig. 2 I may hinge the side wall panels 24 so that they may be folded down within the limits of the securement chains 25 to serve as additional shelves. Desirably the side flanges 26 of said side panels telescope over the edges of the upper and lower cover forming members to complete the enclosure. I may also hingedly affix to the front edge of the table an apron 27 which may be supported in raised position by the brackets 28.

In the embodiment of Fig. 6 the basic table structure is similar to that previously described. The cover, however, comprises a rear member 29 securely affixed to the table top, and a front section 30 hingedly secured to the front edge of the member 29. Preferably hinge 31 is of the piano type. The cover members have appropriate side panels 32, 33, which may align in abutting or overlapping relationship when the cover is closed, according to preference in construction. As shown in Fig. 7 the cover members collectively provide an enclosure. When the member 30 is folded back to the Fig. 6 position in which it is supported by member 29, wall portion 34 provides the auxiliary shelf area and the wall portion 35 forms the guard wall at the rear thereof.

The Fig. 8 embodiment is basically similar to that of Fig. 6 with the exception that the cover forming components 29a and 30a are not provided with fixed side members. Therefore, as in Fig. 2 I hingedly attach to the side edges of the table 2 suitable side forming panels 36 for support when in extended position by the chains or the like 37. An advantage of the constructions of Figs. 6 and 8 resides in the secure support provided by the cover members 29 and 29a, making unnecessary the use of braces such as the members 23 of Fig.

4. Thus, these cabinets may be in actual surface contact with the building wall; and in the Fig. 6 construction particularly, may be set in closely fitting relationship with adjacent kitchen or laundry cabinets.

While I have shown a particular embodiment of my invention, it will be understood, of course that I do not wish to be limited thereto since many modifications may be made; and I therefore contemplate by the appended claims to cover any such modifications as fall within the true spirit and scope of my invention.

What I claim as new and desire to secure by Letters Patent of the United States is:

1. In combination with a table, a foldable cover construction comprising a first cover member fixed to said table at the rear thereof and extending upwardly and forwardly, the upwardly extending portion providing a rear wall and the forwardly extending portion lying above said table surface to provide shelf space when said table is uncovered, vertically extending guide rails fixed to said upwardly extending portion, a second cover member having a wall covering the top area of said table and a wall extending angularly into contact with the table surface to provide the front closure wall of said cover, and roller members secured to said second cover member at the rear edge thereof and riding within said rails, said rollers providing pivots about which said second cover member may be swung through an angle bringing its first-named wall into alignment with said guide rails and then dropped downwardly to support said cover member in raised position with a wall portion extending upwardly from the shelf-forming portion of the first cover member to provide a guard wall at the rear thereof said construction making it necessary that said second cover member be sequentially swung and dropped rather than being concurrently swung and dropped.

2. A cover according to claim 1, in which the forwardly extending portion of the first cover member provides a support for the second cover member when the latter is in closed position.

CARL S. DAYTON.
